UNITED STATES PATENT OFFICE

156,000

DESIGN FOR A BATHROOM SCALE

Lucille E. Hansen, Evanston, Ill., assignor to Hanson Scale Company, Chicago, Ill., a corporation of Illinois

Application January 26, 1949, Serial No. 504

Term of patent 14 years

(Cl. D52—10)

To all whom it may concern:

Be it known that I, Lucille E. Hansen, a citizen of the United States, residing at Evanston, in the county of Cook and State of Illinois, have invented a new, original, and ornamental Design for a Bathroom Scale, of which the following is a specification, reference being had to the accompanying drawing, forming part thereof.

In the drawing:

Fig. 1 is a top plan view of a bathroom scale, showing my new design;

Fig. 2 is a side elevational view thereof; and

Fig. 3 is a front elevational view thereof.

I claim:

The ornamental design for a bathroom scale, substantially as shown.

LUCILLE E. HANSEN.
